UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

HOIST.

Application filed March 5, 1923. Serial No. 622,779.

To all whom it may concern:

Be it known that I, FRED M. SLATER, a citizen of the United States, and a resident of Easton, county of Northampton, State of Pennsylvania, have invented a certain Hoist, of which the following is a specification, accompanied by drawings.

This invention relates to hoists, but more especially to a power driven hoist of the 10 double drum type, in which either drum may be driven from a common driving shaft. Such hoists shown for example, in U. S. Patent No. 1,421,183, granted June 27th, 1922, to Jesse Ditson, are particularly useful 15 for haulage purposes or in connection with other work in which the load is carried by a continuous rope or cable, adapted to be wound upon the haulage or lifting drum as it is unwound from the tail rope drum.

20 Similarly to the patent referred to, the objects of the present invention are to enable two drums, as for instance, a haulage drum and a tail rope drum, to be driven from a common source by improved means and devices, which automatically disconnect one 25 drum and connect the other drum to the driving shaft in accordance with the direction of rotation of the shaft.

30 In accordance with my invention, the opposed drivers carried by the drums respectively are provided with ratchet faces and the main driver, which rotates with the driving shaft, carries a movable member for automatically connecting the main driver 35 to one or the other of the opposed drivers in accordance with the direction of rotation of the driving shaft, but in addition to these elements, other means are included for insuring that the movable member is actuated 40 into engagement with one or the other of the opposed drivers. The movable member may be in the form of a pawl, and is moved or rocked from one side to the other, to engage one or the other of the opposed drivers.

45 Further objects of the invention will hereinafter appear and to all of these ends the invention consists of the hoist described and claimed in this specification and shown in one of its preferred forms in the accompanying drawings, in which

Figure 1 is a longitudinal sectional elevation of the hoist partly broken away,

50 Figure 2 is a transverse sectional view on the line 2-2 of Figure 1 looking in the direction of the arrows, and

Figure 3 is a detail top plan view of a portion of the hoist partly in section, on the line 3-3 of Figure 1.

Referring to the drawings, the base plate A on which the hoist is mounted, is provided 60 with a clamping member or portion preferably in the form of a saddle clamp B having the clamping bolts C for securing the hoist to a column, cross bar or other support. Any suitable motor may be provided for 65 the hoist and in this instance a fluid pressure motor is indicated, having the frame D mounted on the base plate A, and a casing G secured to the frame D by the cap bolts H. Fluid pressure, as for instance compressed air, is supplied to the motor through a suitable inlet, (not shown) controlled by a suitable valve K in the valve chest L adapted to be manipulated by the valve lever O. In this instance, the motor is assumed 70 to be a reversible motor, the reversal of which is controlled by the valve lever O.

A center bearing Q shown in this instance as a tubular support in the form of a shell, having a tubular body and a flanged portion R, in this instance forms a part of the frame D. The opposite end of the center bearing is supported in the gear box S, which may be suitably secured to the base plate A. A center bearing retaining screw 80 U secures the center bearing to the inner wall of the gear box S. The gear box cover X is secured to the gear box by means of the bolts Y. The construction of the motor and frame so far described, has a minimum 85 number of parts, is strong and compact, easily assembled and dis-assembled, and permits ready accessibility to the operative 90 parts of the hoist.

95 A main driving shaft a passing longitudinally through the center bearing Q is supported in the bearings b and c and is connected to be rotated by the motor in any suitable manner. A driving pinion h is keyed to the driving shaft a, and meshes with an intermediate gear o journaled on the counter shaft p mounted in the gear box cover X. The intermediate gear o is provided with the bearings q and r, and an intermediate pinion s in this instance forming a portion 100 of the intermediate gear o, meshes with the internal gear t of the main driver u preferably in the form of a hollow rotatable shaft adapted to rotate on the center bearing Q from which main driver, power is 105 110

- taken for driving either one of the two drums v and x loosely mounted relative to the main driver or rotatable shaft u and rotatable about the driving shaft a . It will thus be seen that the main driver u is connected as by means of gearing to the main driving shaft a . In this instance also one of the drums is conveniently journaled on the center bearing Q .
- 10 The haulage drum v to which one length of the rope w is adapted to be connected, preferably rotates upon the center bearing Q and the tail rope drum x , mounted beside the drum v in line therewith and to which the tail rope y is connected, preferably rotates upon the main driver u as a convenient and compact construction, indicated particularly in Figure 1. Such construction of the drums materially reduces the over-all length of the hoist and produces a compact and well balanced hoist.
- 15 Means are provided for automatically connecting the main driver u to one or the other of the drums v and x in accordance with the direction of rotation of the driving shaft a , and for this purpose the haulage drum v is provided with a driver z preferably in the form of an annular ring or plate having clutch members in the form of teeth 2 on its face merging into the cam surfaces 3. The haulage drum driver z is suitably secured to the haulage drum by means of the bolts 4.
- 20 The tail rope drum x is likewise provided with a driver 5 opposed to the driver z and also preferably in the form of an annular ring or plate having clutch members on its face in the form of teeth 6, facing in the opposite direction from the teeth 2 on the driver z and merging into the cam surfaces 3. The tail rope drum driver 5 is secured to the tail rope drum x by means of rivets 8.
- 25 The main driver u is provided with a radially disposed carrier or driving head u' rigidly fixed thereto and having one or more movable clutch members 9, preferably in the form of shiftable pawls or dogs pivotally and reciprocably mounted thereon within the recesses 10 formed between the projections 12 and projecting from the carrier between the clutch members or ratchet faces of the opposed drivers z and 5, so that the pawls 9 may engage either one of the drum drivers in accordance with the direction of rotation of the driving shaft a and consequent rotation of the shaft u . Each pawl or dog 9, of which there may be one or more, as desired, is preferably mounted on a reciprocable pivot pin 13 and secured thereto as by means of transverse locking pins 14^a. Only one dog 9 need ordinarily be used and the dogs as shown are mounted in the free ends of the driving head u' remote from the shaft u for alternate engagement with the drums to rotate them in opposite directions. The pivot pins are rotatable within the projections 12 of the carrier or head and each pivot pin is provided with a rifled portion 14 engaging a rifle nut 16 held in position by the pins 17. Sufficient clearance is provided for the pawls within the recesses 10 in the carrier, to permit the rifled pivot pin 13 to reciprocate or move longitudinally in the head, and in so moving the rifled connection between the pins and the rifle nuts, causes the pins to rotate about their longitudinal axes, thus rocking the pawls in one direction or the other and causing them to engage one or the other of the opposed drivers, one upon either side of the driving head u' . The rifle pins and nuts constitute means in addition to the cam surfaces of the ratchet teeth 2 and 6 of the opposed drivers for actuating the pawls and insuring that they are moved into engagement with one or the other of the opposed drivers, altho I am not to be understood as limiting the invention to the construction shown, since other equivalent means could be provided for actuating the pawls within the scope of my invention, as defined in the claims appended hereto.
- 30 Obviously, the rifled connection between a pin 13 and a rifle nut 16 normally holds the dog or pawl in either of its driving positions, because the dog is restrained from rocking movement unless relative reciprocation takes place between the pin 13 and the carrier or head u' .
- 35 In the operation of the hoist so far described, if it be assumed that the driving shaft a is rotating clockwise in the direction of the arrow 18, indicated in Figure 2, the main driver u will be rotated by the train of gearing described, in the opposite direction, as indicated by the arrow 19 on the same figure, and the pawls 9 will have been actuated by their rifle pins and nuts into engagement with the teeth 2 on the haulage drum driver z , as indicated in the figures, thus driving the haulage drum v in the same direction as the main driver u , but in the opposite direction to the rotation of the driving shaft a . The arrow 20 in Figure 3 on the haulage drum v , indicates the direction of the rotation of said drum under such circumstances when power is applied to the drum to wind up the tail rope. Under this condition, the tail rope drum x is disconnected from the driving shaft a but is freely rotated in the same direction as the haulage drum v , as the rope is un-wound from said tail rope drum.
- 40 It is to be understood that the width or thickness of the pawls 9 is less than the distance between the opposed ratchet teeth 2 and 6 of the opposed drivers z and 5, so that the pawls cannot engage both sets of teeth at the same time. The device is operative with one pawl only, but several are
- 45 50 55 60 65 70 75 80 85 90 95 100 105 110 115 120 125 130

shown for illustrative purposes. When using one pawl, if a projection 12 should break, for instance, a pawl can be inserted between two other projections 12 and an entire new head is not required. Upon reversing the direction of rotation of the driving shaft *a* and causing it to rotate counter-clockwise in the opposite direction to the arrow 18 in Figure 2, the direction of rotation of the main driver *u* will be reversed, and as the main driver and carrier *u'* start to rotate in the opposite direction to that in which they had been rotated, the cam surfaces of the ratchet teeth operate with the pawls and in addition the rifle pins 13 of the pawls will be rotated about their longitudinal axes by the movement of the rifle nuts 16 and the pawls will be rocked into sure engagement with the ratchet teeth 6 of the opposite driver 5, thus driving the tail rope drum *x* oppositely to the direction of rotation of the driving shaft *a*. In such case, the rope will be wound up on the tail rope drum *x* and the haulage drum *v* will be rotated freely in the same direction as the tail rope drum, as the rope is un-wound from the haulage drum. One drum or the other will be automatically connected to the driver from the driving shaft as often as the direction of rotation of the driving shaft is reversed. In a hoist of the character described, a brake should be provided for one of the drums, and although it is unnecessary to provide a brake for both drums, in some instances two brakes may be preferable, and I have shown a brake for each drum. In this instance, the tail rope drum *x* may be conveniently provided with a flange 21 to which the brake band 22 having a suitable lining is applied. A brake lever 23

is fulcrumed on the base A, at 24, and any suitable mechanical connection, not indicated in detail, may be provided between the brake lever 23 and the brake band 22 for tightening and loosening said brake. Similarly a brake band 25 is applied to the flange 26 of the haulage drum *v* and suitably connected to be operated by the brake lever 27.

50 I claim:

1. In a hoist, the combination of a frame, a driving shaft, two drums rotatable about the driving shaft, a motor connected to operate the driving shaft, opposed drivers 55 carried by said drums respectively, a main driver connected to be rotated by the driving shaft, a pawl pivoted to the main driver for automatically connecting said main driver to one or the other of the said opposed drivers in accordance with the direction of rotation of the driving shaft, and additional means for rocking said pawl about its pivot and insuring that it is moved into engagement with one or the other of 60 said opposed drivers.

2. In a hoist, the combination of a frame, a driving shaft, two drums rotatable about the driving shaft, a motor connected to operate the driving shaft, opposed drivers 70 carried by said drums respectively, a main driver connected to be rotated by the driving shaft, a rifle pin and nut carried by the main driver, and a pawl on said rifle pin for automatically connecting said main 75 driver to one or the other of said opposed drivers in accordance with the direction of rotation of the driving shaft.

In testimony whereof I have signed this specification.

FRED M. SLATER.
